(57) **CLAIM**

The ornamental design for a display screen with graphical user interface, as shown and described.

DESCRIPTION

The FIGURE is a front view of a display screen with graphical user interface showing our new design.

The broken line showing of the display screen and remainder of the graphical user interface forms no part of the claimed design.

The term “iPhone” and the design of the mobile device shown forming part of the claimed design are registered trademarks of Apple, Inc. The term “pepsi” shown forming part of the claimed design is a registered trademark of Pepsico, Inc.
